UNITED STATES PATENT OFFICE

1,981,424

HEAT EXCHANGE DEVICE

Donald W. Lake, Chicago, Ill., assignor to Excel
Auto Radiator Company, Chicago, Ill., a cor-
poration of Delaware

Application June 27, 1934, Serial No. 732,689

3 Claims. (Cl. 257—137)

The invention relates to heat exchange devices and is particularly adapted to be embodied in heaters for automobiles.

One form of the invention is embodied in a heater for automobiles, the heater being of that type in which the water of the cooling system is employed to heat the interior of the automobile.

The heater comprises a core having a plurality of tubes between which the air in the automobile 10 is circulated by a fan so that there will be an exchange of heat between the hot water flowing in the tubes and the air passing between them.

Heaters of the type described above are generally secured to the dashboard of the automobile, 15 the conduits whereby the heated liquid is supplied to the core being led through apertures in the dashboard.

Various means have been employed to mount the heaters on the dashboard, the earlier types 20 of mountings being undesirable as they employed a plurality of bolts extending through the dashboard. This required drilling a plurality of holes through the dashboard and as that surface of the dashboard beneath the hood of the automobile 25 is generally employed as a base upon which much of the electrical equipment of the car is mounted, it is difficult to find clear spaces of the proper distance apart through which the holes may be drilled.

30 In the present embodiment of the invention, a single hole is drilled through the dashboard. The casting or bushing extending through this hole is cored to provide a plurality of passages through which heating medium is led to the radiator core.

35 The radiator core and the fan for advancing the air being heated are mounted on or carried by the casting or bushing.

Other advantages will become apparent as the following detailed description progresses in connection with the accompanying drawings in which—

Fig. 1 is a vertical longitudinal section taken through a heater embodying the invention, the section being also taken through the dashboard of 45 an automobile;

Fig. 2 is a plan section taken on line 2—2 of Fig. 1;

Fig. 3 is a section taken on line 3—3 of Fig. 1; 50 Fig. 4 is a side elevation, partly in section, of a heater which embodies another form of the invention; and

Fig. 5 is a section taken on line 5—5 of Fig. 4.

Referring for the present to Figs. 1 to 3, inclusive, wherein a preferred form of the invention 55 is illustrated, the reference character 10 design-

nates generally a heater particularly adapted to be installed in an automobile to heat the interior thereof. The heater 10 preferably comprises a radiator core 11 which, in turn, comprises upper and lower headers 12 and 13, respectively, which 60 communicate with each other through a plurality of tubes 15 of elongated cross-section.

Mounted upon the tubes 15 and extending transversely thereof are a plurality of fins or vanes 16 which facilitate the exchange of heat 65 between a heating medium flowing through the tubes 15 and air which passes between the tubes 15.

The radiator core 10 is preferably mounted in a housing 18 which is provided with a front 70 wall or portion 19 having a relatively large central opening 20. Disposed in the opening 20 are a plurality of adjustable shutters 21. This construction is well known to those skilled in the art.

The heater illustrated in Figs. 1 to 3 inclusive, 75 is particularly adapted to be connected to the cooling system of the automobile so that hot water from the cooling system will pass into the header 12 and gravitate downwardly in the tubes 15 into the header 13 from whence it is returned to the 80 cooling system.

The means for advancing the heated water through the radiator core 10 preferably comprises pipes or tubes 24 and 25 communicating with and secured to the headers 12 and 13, respectively, and 85 communicating also with passages 26 and 27, respectively, cored in a casting or bushing 28 which projects through the dashboard 29 of an automobile. It will be noted that the tubes 24 and 25 are bent so that they may be brought into registry with the associated ends of the passages 26 and 27. Any suitable means may be provided for securing the tubes 24 and 25 to the casting 28. In this instance, the ends of the tubes adjacent the casting 28 are flared outwardly as at 30 to 95 seat upon frusto-conical surfaces 21 formed upon bosses 32 extending from the casting 28. Nuts 33 secured thereto upon the bosses 32 clamp the flared ends 30 against the frusto-conical surfaces 21. 100

The casting 28 is provided with an integral nut or flange 35 which abuts against the inner side or surface of the dashboard 29. The outer end of the casting 28 is screw-threaded to receive a plurality of nuts 37, one of which abuts against a metallic bar 40 which abuts in turn against the outer surface of the dashboard 29. The function of the bar 40 is to prevent tilting of the heater in a vertical plane and to assist the flanges 105 110

35 and nuts 37 to hold the heater substantially rigid with respect to the dashboard 29.

5 A U-shaped bar or bracket 42 is secured to the flange or nut 35 by bolts 43. Obviously, the U-shaped member 42 may be formed integral with the casting 28 if it is so desired. The legs of the U-shaped bracket 42 are secured rigidly to the housing 18 by any suitable means, such as spot welds.

10 The bracket 45 extending between the legs of the bracket 42 carries an electric motor 46 provided with the usual fan 48. A metallic strap 50 secures the motor 46 to the bracket 45.

15 Screwthreaded into the outer ends of the passages 26 and 27 are tubes or pipes 52 and 53, respectively, to which flexible hoses, not shown, may be secured to connect the heater to the cooling system of the automobile.

20 It is readily apparent that when the heater is to be mounted in the automobile, it is only necessary to drill a hole 55 through the dashboard 29 to receive the casting 28. If it is so desired, the bolts 42 may extend through the flange or nut 35 to engage the dashboard 29 and thus prevent 25 rotation of the casting 28 in the dashboard 29.

When the heater is in operation, the heating fluid circulates through the radiator core 10 as described above. The fan circulates the air within the automobile through the heater between the 30 tubes 11 thereof, the shutters 21 being opened as desired.

35 In Figs. 4 and 5 another embodiment of the invention is illustrated. In this instance, the heater is preferably substantially identical in construction with the heater shown in Figs. 1 to 3, inclusive, and is connected to the heating system of an automobile and supported by the dashboard of the automobile by means substantially identical with those shown in Figs. 1 to 3, inclusive.

40 However, in Figs. 4 and 5 it will be noted that the electric motor, which is provided to advance the air through the radiator core, is designated by the reference character 60 and is mounted on a 45 bar 61 which is attached directly to a housing 62, which has the same function as the housing 18 described above. Substantially the only difference between the heater shown in Figs. 4 and 5, and the heater shown in Figs. 1 to 3, inclusive, 50 is that the electric motor is carried by the hous-

ing of the radiator core instead of by the bracket which supports the housing.

Having thus described my invention, what I claim as new and desire to secure by Letters Patent is:

1. The combination with a heater of the kind described having a radiator core adapted to be mounted upon the dashboard of an automobile and having conduits connected thereto for conducting a heating medium through said core, of means for supporting said heater on said dashboard, said means comprising a separate member extending through said dashboard and having a plurality of passages therethrough, means for detachably securing the ends of said conduits to said separate member in communicating relationship with the said passages therein, and a bracket carried by said member and supporting said radiator core. 80

85

2. The combination with a heater of the kind described having a radiator core adapted to be mounted upon the dashboard of an automobile and having conduits connected thereto for conducting a heating medium through said core, of means for supporting said heater on said dashboard, said means comprising a separate member extending through said dashboard and having a plurality of passages therethrough, means for detachably securing the ends of said conduits to said separate member in communicating relationship with the said passages therein, and a bracket carried by said member and supporting said radiator core. 90

95

100

3. The combination with a heater of the type described having a radiator core disposed within a housing adapted to be mounted upon a dashboard of an automobile, said heater having conduits connected thereto for conducting a heating medium through said core, of means for supporting said heater on said dashboard, said means comprising a member extending through said dashboard, and having a plurality of passages therewith forming parts of said conduits, a 105 bracket carried by said member and supporting said housing, and means carried by said bracket for advancing air through said radiator core. 110
